(57) **CLAIM**

The ornamental design for a beverage container insulator with built-in enclosure, as shown and described.

DESCRIPTION

FIG. 1 is a front bottom perspective view for a beverage container insulator with built-in enclosure, showing my new design;

FIG. 2 is a rear top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top right side perspective view in an open configuration in an environmental view; and,

FIG. 10 is a bottom right-side perspective view in an open configuration.

The broken lines indicate unclaimed portions of the beverage container insulator with built-in enclosure and form no part of the claimed design.

1 Claim, 10 Drawing Sheets
